UNITED STATES PATENT OFFICE.

ERNEST COLEGATE, OF LONDON, ENGLAND.

SNAP-FASTENER.

1,074,247.

Specification of Letters Patent. Patented Sept. 30, 1913.

Application filed December 8, 1911. Serial No. 664,599.

To all whom it may concern:

Be it known that I, ERNEST COLEGATE, a subject of the King of England, and residing at London, in England, have invented 5 certain new and useful Improvements in Snap-Fasteners, of which the following is a specification.

This invention relates to snap fasteners and particularly to the socket portions of 10 those fasteners intended to be attached to envelopes, paste board, boxes, paper fabric, and similar substances. Such socket portions are not intended to release the corresponding stud member when the latter has 15 once been made to engage therewith.

The object of this invention is to provide a socket of this type which may be cheaply made and easily assembled.

According to this invention the socket portion 20 comprises a base plate having spiked projections which are bent at right angles to the plane of the plate, their lower portions being bent over the flange of an annular cover, thereby connecting the cover 25 which contains an annular spring member to the base plate, the pointed ends of all the spikes subsequently serving to rivet the socket to its supporting surface. This arrangement can be more quickly assembled 30 than previous constructions in which alternate tongues, after being passed through slots in the base of the spring-containing casing, were bent over to connect the component parts of the socket together, a further 35 advantage of the present arrangement lying in the fact that all the spikes, as opposed to the alternate ones only, are available to rivet the completed socket to its supporting surface, as well as for the purpose 40 of holding the component parts of the socket together prior to its being attached to its supporting surface.

In the accompanying drawings which 45 show one construction of socket member in accordance with this invention, Figure 1 is a vertical section through the cover, Fig. 2 is a similar view of the spring member. Fig. 3 is a plan of the base plate before the spikes thereon have been bent upward. Fig. 4 is a section through a socket member after the parts have been assembled, Fig. 5 is a 50 perspective view of a completed socket member, and Fig. 6 is a similar view showing the socket member riveted to a strip of paper or the like.

In all the figures the socket member is represented of a size larger than that usually employed.

The annular cover or casing A is stamped from sheet metal and has a flange A' surrounding its annular recessed portion. Adapted to lie within the cover is an inner spring member B comprising an annular cup having spring fingers B' adapted to engage the stud portion of the fastener (not shown). The material from which the spring fingers are made is preferably such that they cannot be bent back after once engaging the stud. That is the snap fastener of which the socket member herein described is a part is of the type or class styled "non-separable." In the particular embodiment of the invention illustrated the outer end wall of the cover A is in direct contact with the spring fingers B' so that it acts as a positive stop to movement of the fingers in the direction necessary to release the stud member. The base plate C is also stamped from sheet metal and, in the construction illustrated, has four spikes C' projecting therefrom. The lower portions of the spikes nearest the edge of the base plate are first bent over the flange A' of the cover, thus uniting the component parts together and forming a socket having spikes 80 projecting vertically from its flange suitable for attachment to paper or the like. The projecting ends of all the spikes C' are subsequently passed through and riveted over on to the supporting surface of paper, 85 cardboard, linen or the like D as shown in Fig. 6, the paper being first perforated to receive the projecting portion of the cover A in the usual manner.

In the construction illustrated the base 95 plate is provided with a small central aperture C² to facilitate the assembly of the parts, but the depth of the recess in the cover A is sufficient to permit of the stud portion of the socket engaging the latter 100 without having to make contact with the base plate which thus serves as a shield to prevent the spring members B' being tampered with when the socket is attached to articles of such a nature that its rear surface is exposed.

It will be understood that the number of projecting spikes employed will vary in accordance with the purpose for which the fastener is intended.

What I claim as my invention and desire to secure by Letters Patent is:—

1. The herein described socket member of a snap fastener comprising a base plate, an annular cover having at one end an aperture through which the stud member of the fastener passes to engage the socket portion and having at its opposite end an outwardly projecting flange that bears against the base plate, and spurs on the base plate bent over said flange to connect the component parts of the socket together, with the pointed extremity of each projecting from the flange and base plate and constituting means for securing the completed socket to a support.
2. The herein described socket member of a snap fastener comprising a hollow cover section having a laterally projecting annular flange at one end and provided at its other end with an aperture through which the stud member of the fastener is adapted to extend, a base plate bearing against the flange of the cover section and having a plurality of spurs which are bent over and against said flange, at intermediate points in their length, to secure the cover section on the base plate, the free ends of said spurs projecting from and constituting the means for securing the entire device to a support, and a spring member arranged within the cover section to engage the stud member of the fastener when it is inserted in the socket member.
3. The herein described socket member for a snap fastener comprising a hollow cover section having a laterally projecting annular flange at one end and provided at its other end with an aperture through which the stud member of the fastener is adapted to

extend, a base plate bearing against the flange of the cover section and having a plurality of spurs which are bent over and against said flange, at intermediate points in their length, to secure the cover section to the base plate, the free ends of the said spurs projecting from and constituting the means for securing the entire device to a support, and spring fingers arranged within the cover section to engage the stud member of the fastener when inserted in the socket, said fingers bearing against the end wall of the cover section so that they are prevented from moving in a direction permitting withdrawal of the stud from the socket.

4. The herein described socket member of a snap fastener comprising a base plate provided with a plurality of peripheral spurs, a hollow cover having an aperture formed in its top and provided at its opposite end with an annular outwardly projecting flange which bears against the base plate, each of the spurs on the base plate being bent, at an intermediate point in its length, to extend first partly over said flange, to secure the cover and base plate together, and then away from the base plate, and providing means for securing the attached cover and base plate to a support, and means within the cover for engaging the stud member of the fastener.

In testimony whereof I have signed my name to this specification in the presence of two subscribing witnesses.

ERNEST COLEGATE.
